UNITED STATES PATENT OFFICE.

LUDWIG LOHR, OF PHILADELPHIA, PENNSYLVANIA.

PROTECTOR FOR WINDOW-CLEANERS.

1,017,982.

Specification of Letters Patent. Patented Feb. 20, 1912.

Application filed November 1, 1911. Serial No. 657,927.

To all whom it may concern:

Be it known that I, LUDWIG LOHR, a subject of the Emperor of Germany, but having declared my intention of becoming a citizen 5 of the United States, residing at Philadelphia, in the county of Philadelphia and State of Pennsylvania, have invented new and useful Improvements in Protectors for Window-Cleaners, and of which the following is a specification.

My improvements relate to means for safeguarding a person cleaning windows from falling from the same, and consists principally of means to provide a back support for the person while cleaning windows.

My improvements will be more fully understood taken in connection with the accompanying drawings forming part hereof, and in which:

Figure 1 is a side view of my protector, shown mounted on a window sill. Fig. 2 is a front view of the protector. Fig. 3 is a top view of the protector. Fig. 4 is a view showing extension bars to render the protector adaptable for different thicknesses of walls. Fig. 5 is a cross section on line 5—5 of Fig. 4, and Fig. 6 is a top view of the said extension bars.

Referring now to the drawings for a further description of my invention, A and A¹ are the sides of the protector, and B is the back thereof. The sides A and A¹ are formed of the uprights a and a¹ of wood, and these are connected together by means of extension bars a² and a³, these bars a² and a³ have each a socket a⁴ encircling the uprights a and a¹ and the latter are held in place by the pin a⁵ in such a way that the uprights may to a certain degree swing about the pins a⁵, for a purpose to be described.

The extension bar a² is provided with a slot a⁶ and a toothed rack a⁷ is formed at either edge of said slot, the extension bar a³ is provided with a bolt hole and slots to lighten the bar and has at either edge a flange a⁸ bearing on the teeth of the bar a². Near the bolt hole or in line thereof is provided one or more teeth adapted to engage between the teeth of the bar a², so that when the two bars a² and a³ are clamped together by means of a bolt a⁹, the two bars a² and a³ form one rigid member. The tooth or teeth near the bolt hole of the bar a³ being adapted to fit any of the teeth in the rack a⁷ of the bar a², so that the distance between the sockets a⁴ of the respective bars a² and a³ may be increased or decreased as required.

On the uprights a and a¹ are adjustable stops c¹ having lugs c² and c³ to engage the inner and outer sill of the window, and as 60 these sills may be of different level as shown in Fig. 1 these stops c¹ may be set at any height on the uprights by means of the thumbscrews c⁴.

At the lower extremity of the uprights a 65 is secured an adjustable back stop d¹ comprising the threaded stock d² and jam nut d³. Just above the points where the bars a³ and a² are joined to the uprights a and a¹ respectively, are provided sliding stops s¹, which 70 normally rest against the projection s² of the bars a² and a³, by the force of the helical spring s³ mounted in the thimble formed on the respective bars a² and a³ as shown in Fig. 4. These sliding stops s¹ are provided 75 to readily disengage the protector from the sill of the window, when it is desired to remove the protector from the window sill. For the purpose of removing the protector from a window these sliding stops are moved 80 upward disengaging them from the respective projections s², and the springs s³ force the lower ends of the uprights a and a¹ outward as will be readily understood from the drawings, Figs. 1 and 4. The sliding stops 85 s¹ are held in place on the uprights a and a¹ by means of screws s⁴, and a slot s⁵ is formed in the back plate s⁶ which terminates in the handle s⁷ of the stop s¹.

To the uprights a of the sides A and A¹ 90 are secured the brackets f¹ by means of sockets f² and these brackets f¹ are provided with hinges f³, to which the rods b forming the back B are secured. The rods b secured to the various hinges f³ form the back B, 95 and the sides A and A¹ may be folded onto the same when the protector is not in use, as will be readily understood.

The construction and mode of operation of the different parts constituting my improved protector for window cleaners, having been fully described, what I claim as new and desire to secure by Letters Patent is:

1. A protector for window cleaners, comprising a back, two sides hinged thereto and 100 composed of uprights connected by extension bars, adjustable stops on said uprights to suit the different levels of the inner and outer window sills, and an adjustable back stop at the lower end of the outer uprights 105 110

substantially as and for the purposes set forth.

2. A protector for window cleaners comprising a back, two sides hinged thereto and composed of uprights and adjustable extension bars, the said bars pivoted to the said uprights, adjustable stops on said uprights to suit the levels of the inner and outer window sills, sliding stops on said uprights 10 adapted to impinge on lugs formed on the

extension bars, helical springs mounted in thimbles on the extension bars and normally keeping the sliding stops in contact with the said lugs, and adjustable back stops at the lower ends of the outer uprights, substantially as and for the purposes set forth. 15

LUDWIG LOHR.
